UNITED STATES PATENT OFFICE

WILLY FROMM, OF FRANKFORT-ON-THE-MAIN, GERMANY, ASSIGNOR TO UNITED SHOE MACHINERY CORPORATION, OF PATERSON, NEW JERSEY, A CORPORATION OF NEW JERSEY

ABRADING MACHINE

Application filed May 16, 1925, Serial No. 30,779, and in Germany June 2, 1924.

This invention relates to abrading machines and is herein illustrated as embodied in a machine for grinding the cutting edges of curved knives such, for example, as heel 5 breasting knives which are used to shape the breasts of the heels of boots or shoes.

A heel or heel base of the type comprising a plurality of heel lifts requires a breasting 10 operating after it has been attached to the shoe. The breasting operation is commonly performed by a knife the face of which is curved to impart the desired curvature to the heel breast, this curvature being usually in 15 the form of an arc of a circle. Inasmuch as the shank portion of a shoe sole, at its junction with the breast of the heel, may have either a flat or a convex outer surface, and since the heel breasting knife should cut the material of the heel down to the surface of 20 the sole and not beyond, the cutting edge of the breasting knife should have a profile (when viewed from the plane of symmetry of the knife in a direction perpendicular to the surface of the knife) which corresponds to 25 the transverse contour of the shank of the sole, the profile of the cutting edge being concave if the shank of the sole is transversely convex and being straight if the shank of 30 the sole is flat. Furthermore, heel breasting knives are sometimes made with one end or shank portion of the knife having the same transverse curvature as the blade portion while in other cases the shank portions of 35 curved heel breasting knives are flattened the better to adapt the knives to be clamped in place in the breasting machine.

With the foregoing in mind, one object of the present invention is to provide an improved abrading machine wherein curved 40 kinds of either of the types referred to may be readily positioned and advantageously operated upon for the purpose of producing cutting edges having either curved or straight profiles.

To the accomplishment of this object one

feature of the invention consists in the provision, in a machine for grinding curved knives of the type in which the cutting edge is transverse to the axis of curvature of the knife blade, of a work holder mounted for 50 oscillation to traverse the work across the face of the grinding element and for adjustment into such a position relatively to its axis of oscillation that the cutting edge will be ground when the desired curved profile or 55 into such other position relatively to said axis that the cutting edge will be ground with a straight profile.

In the illustrated embodiment of this feature of the invention the grinding element 60 comprises a wheel having a crowned periphery and the work holder is mounted for oscillation about an axis at right angles to the axis of rotation of the grinding wheel and for tilting or angular adjustment into either 65 a position wherein the knife blade is parallel to the axis of oscillation of the work holder for the grinding of a cutting edge having a straight profile, or into such other position that the knife blade will be inclined 70 with respect to said axis for the grinding of a cutting edge having the desired curved profile.

It is desirable that the edges of knives of this type have a substantially uniform bevel 75 throughout their width and another feature of the invention consists in providing adjustments so that the axis of oscillation of the knife during grinding may be positioned to coincide with the center of curvature of the 80 knife edge by which means this desired result is attained, whether the profile of the edge be straight or curved.

Another feature of the invention consists in providing, in a machine fitted for grinding such a substantially uniform bevel, 85 means for adjusting the angle of the bevel.

Further to facilitate effectively supporting in operative position knife blades having either flat or transversely curved end or 90

shank portions, another feature of the invention consists in the provision, for use in an abrading machine, of an improved work holder constructed and arranged to engage separated areas on opposite sides of the shank portion of the knife in such a manner that blades having flat or curved shank portions may be supported with equal facility and without any perceptible distortion of the shape of either type of knife.

A further feature of the invention consists in the provision of a novel fixture for the purpose of centralizing the knife blades transversely with respect to the work engaging portions of the work holder.

It will be understood that the invention, which is herein illustrated as being embodied in a machine for operating upon heel breast-
20 ing knives, is in no respect limited to the particular type of work to be operated upon other than may be determined from the scope of the appended claims.

The invention is more fully described in the following specification and shown in the accompanying drawings, in which:

Fig. 1 is a side elevational view of a grinding machine constructed in accordance with the present invention and shows the work holder in a vertical position supporting a heel breast-
30 ing knife of the type having a curved end or shank portion;

Fig. 2 is a side elevational view of the device shown in Fig. 1 with the work holder shown in tilted position relatively to the grinding element and supporting a blade of the type having a flat end or shank portion;

Fig. 3 is a top plan view of the device shown in Fig. 1 and illustrates the construction of the work holder and its adaptation to a blade having a curved shank portion; and

Fig. 4 is an enlarged plan view of the work holder showing it supporting a blade having a flat shank portion, and showing also the fixture for centralizing the blade relatively to the clamping means.

As shown in the drawings, the machine comprises a work holder 2 adapted to support a heel breast-
50 ing knife 4 for movement across the crowned peripheral face of a grinding wheel 6 and for presentation to the face of the wheel in a tilted position, as shown in Fig. 2, for the grinding of a cutting edge of concave profile, or in a vertical or upright position, as shown in Fig. 1, for the grinding of a cutting edge of straight profile. The work holder 2 is designed and constructed to support with equal facility knives having either transversely curved or flat ends or shank portions without produc-
60 ing any perceptible distortion of the shape of either type of knife. To this end, a yoke or body member 30 is rigidly secured to the upper extremity of a supporting rod 28 and is formed with two cylindrical bearing mem-

bers 36 extending from its opposite sides, the yoke 30 carrying, between the bearing members, two fixedly positioned cylindrical clamping extensions 32. The extensions 32 are symmetrically disposed with respect to the median plane A—B of the work holder, as shown in Fig. 4. (The term "median plane" as used herein is intended to indicate a vertical plane passing through the holder equi-distant from the extensions 32).

Mounted within the bearing members 36 are headed pins 34, each being rigidly secured at one extremity thereof to a bridge or span member 38 carrying a set-screw 40. On the side of the bearings 36 opposite the bridge member 38 a second yoke 42 is slidably mounted to carry pivotally two additional cylindrical clamping extensions 48.

The yoke 42 is slidably mounted on the pins 34 and is normally held in engagement with the heads 44 of the pins by means of springs 46. The set-screw 40 may be turned to produce relative movement between the rigidly mounted clamping extensions 32 and the pivotally mounted clamping extensions 48 to

clamp and hold in supported position a blade whose shank has been inserted between them. By arranging the clamping extensions in such a manner that clamping pressure is

equally applied upon separated areas similarly located on the opposite sides of the shank portion of the knife and symmetrical-
90 ly disposed with respect to the longitudinal center line of the knife, it will be seen by an inspection of Figs. 3 and 4, that there will be no perceptible tendency on the part of the clamping members to distort the shape of any knife clamped thereby, whether its shank be curved or straight.

For the purpose of providing means to centralize a knife with respect to the work engaging portions 32 and 48 of the work holder, the yoke 30 is provided with a ridge 52 which extends coincidentally with the vertical median plane of the holder and upon which ridge a fixture 50 is adapted to be positioned. The fixture 50 is formed with a channel or groove corresponding to and adapted to receive the ridge 52 of the yoke 30. The fixture 50 has formed upon it, symmetrically positioned with respect to the groove or channel, two downwardly extending arms 54 for centralizing a knife transversely with respect to the clamping members 32 and 48, as shown in Fig. 4.

As hereinbefore pointed out, the device is designed to operate on a supported blade to impart thereto a cutting edge of either straight or concave profile, and to the accomplishment of this object the work holder 2 is mounted relatively to the grinding wheel 6 in the following manner: The extremity of the supporting bar 28 opposite the work holder is non-rotatably mounted within a sleeve 26 to permit longitudinal sliding ad-

120
125
130

justment, the extent of adjustment being controlled by a hand wheel 25. The sleeve 26 is tiltably supported at 18 upon a gage bar 12 for movement into a plurality of positions, as shown by Figs. 1 and 2, and the positioning of the sleeve member 26 is controlled by a spring pressed plunger 20 carried by the sleeve and adapted for removable engagement with one of a plurality of apertures or 10 depressions, such as 22, 24 formed in a downwardly extending, rigid arm 27 carried by the gage bar 12. Since a cutting edge having a straight profile will be imparted to the blade when it is presented to the grinding 15 element in a vertical position, and a cutting edge having a curved profile will be imparted when the blade is presented in a tilted position, as will be later explained, the single tilttable adjustment is effective to determine and control the shape of the cutting edge imparted to the blade during the grinding 20 operation.

The gage bar 12 has markings 16 formed on its surface to be used, in co-operation 25 with a face 15 of a clamping head 14, as a gage in determining the magnitude of the radius of oscillation of the work holder about a vertical axis 8, the face 15 of the clamping head being located to coincide with 30 the vertical axis of oscillation. The work holder is mounted to oscillate about a pin 9 coaxial with the axis 8 carried by the clamping head 14 and journaled within a bearing member 11 located within the central plane 35 of the rotary grinding element 6 (i. e., within a plane disposed at right angles to the rotary axis of the grinding element and equidistant from the opposed side faces of the discal grinding element) for longitudinal adjustment within the guideway 10.

In operation, when it is desired to impart a cutting edge having a straight profile to the blade, the holder is positioned as shown in Fig. 1 in which the cutting edge of the 45 blade 4 forms a portion of an arc of a circle in a horizontal plane whose center is located in the central plane of the grinding element. Furthermore, the parts are so adjusted that the center of said arc is made substantially to coincide with the axis of oscillation of the 50 holder. This adjustment is effected by the proper longitudinal positioning of the gage bar 12 in the clamping head 14, to bring the center of curvature of the knife edge into 55 the axis 8, and by the longitudinal positioning of the bearing member 11 in the guideway 10 to bring the knife to the face of the grinding element 6. The upright blade may then be oscillated across the face of the grinding element to produce a cutting edge of straight 60 profile and of uniform bevel. This is because the knife edge always remains in a vertical circular cylinder about the axis 8, and the grinding element 6 will intersect this cylinder always at the same height, cutting it in

a horizontal circle. This circle, when viewed perpendicularly to the surface of the blade, will project into a straight line, thus having a straight profile, according to the terminology herein used. When it is desired to 70 impart a concave cutting edge to the supported blade, the holder is moved into the position shown in Fig. 2 to hold the knife tilted toward the grinding element 6 (i. e., with the axis of curvature of the blade at an angle to the axis of oscillation), the adjustments 8-10, 12-14, being made to bring the axis 8 to the center of curvature of the 75 said cutting edge. The cutting edge will be a horizontal circle for the same reason as before, but the plane of the circle will be now oblique to the longitudinal axis (or the axis of curvature) of the blade and the edge will appear curved when viewed perpendicularly to the surface of the blade and will have what 80 is herein termed a curved profile.

It is apparent that, when the work holder is 85 adjusted relatively to the grinding element in such a manner that the axis of oscillation of the holder coincides with the center of the 90 circle of which the cutting edge of the blade forms an arc (as above described), whether the holder is adjusted to grind blades with straight or curved profiles, the grinding operation will produce a cutting edge having a 95 substantially uniform bevel.

It will be seen that by varying the position of the work holder within the sleeve 26 by means of the hand wheel 25, the cutting edge of the knife will be presented to various 100 points along the periphery of the grinding element to vary the angle of bevel produced by the grinding operation.

Having thus described my invention, what I claim as new and desire to secure by Letters 105 Patent of the United States is:

1. In a device of the class described, the combination with an abrading element, of a work holder mounted for oscillation about an axis lying in the plane of movement of the abrading element to traverse a blade, having a transverse curvature, across the face of the abrading element and for adjustment in said plane into one angular position relatively to its axis of oscillation for the grinding of a cutting edge having a curved profile and into another angular position in said plane relatively to said axis for the grinding of a cutting edge having a straight profile.

2. In a device of the class described, the combination with a grinding wheel, of a work holder adapted to hold a knife blade having a transverse curvature, said work holder being mounted for oscillation about an axis at right angles to the axis of rotation of the grinding wheel and for tilting adjustment into one position wherein the axis of curvature of the knife blade is parallel with respect to the axis of oscillation of the work holder for the grinding of a cutting 130

edge having a straight profile and into another position wherein the knife blade is positioned with its axis of curvature inclined with respect to said axis of oscillation for the grinding of a cutting edge having a curved profile.

3. In an abrading machine, a grinding element, a work holder adapted to hold a curved knife blade having a cutting edge transverse to its axis of curvature, said work holder being arranged to be oscillated about an axis of oscillation and being mounted for tilting adjustment, relative to the axis of oscillation, into any one of a plurality of positions and for oscillation in any of said positions across the face of the grinding element, and means to vary the axis of oscillation to cause it to coincide with the axis of curvature of the cutting edge, whereby the cutting edge of the knife will be ground with substantially a uniform bevel.

4. In an abrading machine, a grinding element, a work holder arranged to be oscillated about an axis of oscillation, said work holder being mounted for tilting adjustment, relative to the axis of oscillation, into any one of a plurality of positions and for oscillation in any of said positions across the face of the grinding element, means to vary the radius of oscillation, and a gage for determining the radius of oscillation.

5. In an abrading machine for operating on blades having a transverse curvature, a grinding wheel, a blade holder movable about an axis in the plane of the wheel to carry a blade across a face of the grinding wheel in a grinding operation, said blade holder being adjustable angularly in said plane, relatively to said axis, whereby movement of the holder will impart either a straight or curved cutting edge to the blade during the grinding operation, and means to vary and control the angle of bevel produced by the grinding operation.

6. In a machine for operating upon an elongated cutter blade having a transverse curvature and with a cutting edge formed at one extremity of the blade, a grinding element, means to move the blade relatively to the grinding element about an axis of oscillation with the longitudinal axis of the blade parallel to the axis of oscillation for the grinding of a straight cutting edge, and means to present the blade to the grinding element with the longitudinal axis of the blade at an angle to the axis of oscillation for the grinding of a curved cutting edge.

7. In an abrading machine for operating on blades having a transverse curvature, an abrading element, a pivot located within the central plane of the grinding element, a work holder mounted for oscillation about said pivot, and means to permit angular variation of the work holder relatively to said pivot whereby a cutting edge with a profile

that is either straight or that has a pre-determined curvature may be produced.

8. In an abrading machine, a work holder comprising relatively movable members adapted to clamp and support knives having either flat or curved shank portions without causing distortion of the shape of either type of knife.

9. In an abrading machine, a work holder comprising two curved work-engaging extensions positioned in a plane perpendicular to the median plane of the holder and symmetrical with respect thereto, and a movable clamping piece arranged for movement relatively to the curved extensions to cooperate with said extensions for supporting and clamping curved knives having straight or curved shank members in a position so that the axis of curvature of the blade coincides with the median plane of the holder.

10. In an abrading machine, a grinding element, a work holder adapted to hold a curved knife blade having a cutting edge transverse to its axis of curvature, said work holder being arranged to be oscillated about an axis of oscillation and being mounted for tilting adjustment, relative to the axis of oscillation, into any one of a plurality of positions and for oscillation in any of said positions across the face of the grinding element to grind a substantially uniform bevel on the knife, and means for varying the angle of said bevel.

11. In an abrading machine, a work holding device comprising clamping members adapted to contact with the opposite sides of the work at separated areas, and a fixture cooperating with the clamping members for centering the work with respect to the median plane of the holder prior to applying the clamping pressure.

12. In an abrading machine, a work holder for cutting blades having, in combination, a plurality of work clamping members, and a fixture adapted to be supported by one of the clamping members to cooperate therewith in centering a blade within the holder.

13. In an abrading machine, a holder for cutting blades comprising a pivotally mounted member having a plurality of rounded extensions for engagement with one side of the blade, a member having a plurality of fixedly positioned rounded extensions mounted thereon for cooperative engagement with the opposite side of the blade and means for moving said members toward each other to clamp and support the blade within the holder.

14. In an abrading machine, a grinding element, a bar mounted for oscillation about a pivot lying within the central plane of the grinder, a sleeve supported by the bar, a work holder mounted within the sleeve, and means to vary the position of the work holder with

in the sleeve to vary the angle of bevel produced by the grinding operation.

15. In an abrading machine, a grinding element, a bar mounted for oscillation about a pivot adjustable within the central plane of the grinding element, a sleeve supported by the bar, a work holder mounted within the sleeve, means to tilt the sleeve about the bar to vary the angle of presentation of the supported work to the grinding element, and means to vary the position of the work holder within the sleeve to vary the angle of bevel produced by the abrading operation.

15 In testimony whereof I have signed my name to this specification.
